UNITED STATES PATENT OFFICE.

GIDEON B. MASSEY, OF NEW YORK, N. Y., ASSIGNOR TO JACOB LORILLARD, TRUSTEE, OF SAME PLACE.

COMPOUND ENGINE.

SPECIFICATION forming part of Letters Patent No. 252,485, dated January 17, 1882.

Application filed December 2, 1881. (No model.)

To all whom it may concern:

Be it known that I, GIDEON BLACKBURN MASSEY, of the city, county, and State of New York, have invented certain new and useful 5 Improvements in Compound Engines, of which the following is a full, clear, and exact description.

My improvements relate to the class of engines in which low-pressure cylinders for using 10 the exhaust-steam are combined with the cylinders using steam under high pressure.

The object of my invention is to obviate the difficulty heretofore experienced from back-pressure and long openings or connecting-pipes, which I accomplish by direct and continuously open connections between the two cylinders and a compound piston in the high-pressure cylinders, whereby the primary and secondary exhausts are regulated, as hereinafter 15 described and claimed.

Reference is to be had to the accompanying drawings, forming part of this specification, in which similar letters of reference indicate corresponding parts in all the figures.

25 Figure 1 is a longitudinal section of the engine. Fig. 2 is a longitudinal section of the high-pressure cylinder in a plane at right angles to Fig. 1.

A is the high-pressure cylinder. B is the 30 low-pressure cylinder, shown as bolted directly to a cored side extension, a, of the cylinder A; but the two cylinders may be cast together and cored as shown. The cylinders communicate by ports b b' through the connection a at the 35 ends of cylinder B, opening into cylinder A a distance from its ends equal to about half the length of the stroke. The ports b b' are connected for reversing the engine, and in connection with the ports b b' reversing-valves 40 c c are fitted for operation to open and close them simultaneously by a hand-lever, d. These valves may be dispensed with in a stationary engine, or one designed to work in one direction only.

45 At the ends of cylinder A there are exhaust-ports e e and steam-ports e', communicating with the main steam and exhaust openings f f', and at the mid-length of cylinder A is an exhaust-port, g. h h' h' are valves fitted in con-

nection with ports e and operated by suitable 50 connections from a rocking lever or link at i. The lever i will be moved by eccentrics on the main shaft k.

l l' are pistons in cylinder A, connected on rod m.

n is the slide of the piston-rod, connected by a rod, o, to one crank of the shaft k.

q is the piston of cylinder B.

p is the piston-rod from slide q', that connects by rod r to a second crank on shaft k, 60 the two cranks being quartered. The space between the two pistons l is slightly less than the length of stroke, so that the middle or secondary exhaust-port, g, is continuously between the pistons, and at half-stroke both primary exhaust-ports b are covered, the piston q of cylinder B being at the same moment at the end of its stroke. In the drawings the pistons l are shown at half-stroke, moving downward. At this point the steam is cut off from the 70 boiler.

The operation is as follows: Steam entering through the upper steam-port, e', piston l is forced down, at half-stroke, steam-valve h' is closed, thereby cutting off steam from the 75 boiler, and at this point, piston l passing port b, the steam exhausts on piston q of cylinder B, which is forced downward simultaneously with piston l by the force of expanding steam until piston l reaches the end of its stroke and piston q is at half-stroke, when piston l commences 80 its return-stroke, while piston q continues downward. As soon as piston l passes port b steam from cylinder B exhausts through ports b and g to the open air or condenser. At the 85 same instant upper exhaust-valve h is opened and the steam shut in the upper end of cylinder A is exhausted through port f, which communicates with exhaust-port g. It will be seen that the piston l returns through the first half 90 of its return-stroke against steam after expansion almost to its maximum, so that this engine is relieved of almost eighty per cent. of back-pressure exerted in the ordinary compound engine. In case condensers are used a vacuum 95 may be obtained through the last half of the return-stroke in cylinder A in addition to that through the entire stroke of piston of cylinder

B, which will more than overbalance the back-pressure on piston *l* through the first half of its return-stroke.

It is to be observed that this engine has no long openings to connect the high and low pressure cylinders or receiver between the two, which reduces the pressure of the expanding steam before it reaches the low-pressure cylinder by increase of volume and by condensation; nor has it any working-valves to the low-pressure cylinder, the pistons of high-pressure cylinder serving in place of valve to open and close the ports. In reversal the connected ports *b b'* allow exhaust to the same end of cylinder B as before, thus maintaining the lead of a half-stroke of the high-pressure cylinder.

Having thus fully described my invention, what I claim as new, and desire to secure by Letters Patent, is—

1. In compound engines, the combination of a high and a low pressure cylinder, each having a single chamber and connected to the other by short direct ports, the high-pressure cylinder having steam-ports at its ends and exhaust-ports both at its mid-length and its ends, substantially as shown and described.

2. In compound engines, the combination of the high-pressure cylinder A, having two pistons upon the same rod, and provided with steam-ports *c* at its ends and exhaust-ports *e* at its ends and *g* at its mid-length, and the low-pressure cylinder B, having a single piston and communicating with cylinder A by short direct ports *b b'*, the said cylinders having each a single chamber, substantially as shown and described.

3. The combination and arrangement of the stationary reversing-valves *c c* with the ports *b b'* and their connecting-cores between the high and low pressure cylinders of a compound engine, substantially as shown and described.

4. The combination of direct exhaust-ports *b b'*, connected by cores and reversing-valves *c*, with the cylinders A B, substantially as shown, to allow reversal of the engine, and maintaining the proper lead of the high-pressure pistons.

GIDEON B. MASSEY.
